UNITED STATES PATENT OFFICE.

WILLIAM ERASTUS WILLIAMS, OF WILMETTE, ILLINOIS.

STEEL END FOR CARS.

Application filed September 3, 1924. Serial No. 735,587.

To all whom it may concern:

Be it known that I, WILLIAM ERASTUS WILLIAMS, a citizen of the United States, and a resident of Wilmette, county of Cook, 5 and State of Illinois, have invented a new and useful Improvement in Steel Ends for Cars, of which the following is a specification.

The object of my invention is to produce 10 a pressed steel end for a freight car that will be stiff in every direction and require the least metal for furnishing the requisite stiffness for a car end.

Reference will be had to the accompanying 15 drawing in which Figure 1 is a front elevation of my end.

Figure 2 is a transverse sectional portion on line 2—2 of Fig. 1.

Figure 3 is a transverse section on line 20 3—3 of Fig. 1.

Figure 4 is a transverse section on line 4—4 of Fig. 1.

Figure 5 is a transverse section on line 25 5—5 of Fig. 1.

A common practice heretofore in making 30 steel ends for freight cars has been to press corrugations either vertically or horizontally more or less parallel to each other, so that the end may be stiff in one direction but 35 relatively weak in another direction. The ends heretofore most generally used transmit the load either entirely across to the end posts or entirely up and down from the sill to the roof sections leaving more or less neutral axis zones in the other directions.

With my invention I arrive at almost 40 a complete uniform stiffness in every direction, so that the end thrust of the cargo within the freight car is transferred as a 45 unit to all four sides of the ends which is a great desideratum.

I arrive at the stiffening of my end sheet by a series of depressions pressed within 45 the sheet in a peculiar arrangement in a manner to avoid a direct neutral axis.

In the drawing 1 indicates the flat plate portion of the end, 2 indicates the side flanges of the end, and 3 indicates the top flange.

A flange on the bottom indicated by 4 which 50 is substantially like the side flanges 2 is shown only by dotted lines in Fig. 1.

Within the body of the sheet I emboss a series of annular cup shaped portions indicated by 5 see Fig. 5, the cup side preferably 55 being in the interior of the car.

This annular cup shaped portion 5 surrounds a central projection 6 which projection is in some respects similar to the form of some cake baking pans which have a central projection extending up through the body of the cake to be baked therein save only that my projection 6 is not perforated but has a solid bottom, as shown in the figures.

These annular cup shaped portions are connected horizontally to each other by means of depressions 7, the word depression referring to the inside of the car. Of course, this will produce a male projection on the 70 outside of the car.

Corresponding vertical depressions 8 connect the annular cups 5 in a similar manner to the horizontal depressions 7.

Were it not for the central projections 6 75 on the annular cup 5 the neutral axis would lie across through the projections 7 and 8 and thus I would have a neutral axis in each direction not stiffened by any depression, rib or corrugation, but by means of the central 80 projections 6 there is no direct line neutral axis, so that any line of rupture or neutral axis of bending moment across the plate will be compelled to follow in and out and around the depressions 7 and 8 and the annular cups 5 thus making a more or less truss effect as involved in the bending stresses in a sheet of this class.

What I claim is:

1. A car end structure stiffened by annular depressions connected to each other by depressed cross ribs merging into the annular depressions, and said annular depressions having projections extending upward in their central regions to the normal flat 95 surface of the plate.

2. A car end structure, stiffened by horizontal and vertical depressions in the flat

sheet, and said depressions merging at their intersections into ring shaped depressions, and the latter provided with central stiffening projections.

5 3. A car end structure, stiffened by horizontal and vertical depressions in the flat sheet, and said depressions merging at their intersections into ring shaped depressions, and the latter provided with central stiffen-

ing projections, and the said sheet flanged 10 on its edges.

Signed at Chicago, in the county of Cook, and State of Illinois, this 30th day of August, 1924.

WILLIAM ERASTUS WILLIAMS.
